LAVATORY FITTING

Harper Landell, Fort Washington, Pa., assignor to Speakman Company, Wilmington, Del.

Filed June 2, 1972, Ser. No. 259,359

Term of patent 14 years

Int. Cl. D23—01

U.S. Cl. D23—32

FIG. 1 is a front elevational view of a lavatory fitting showing my new design;

FIG. 2 is a top plan view thereof;

FIG. 3 is a bottom plan view thereof;

FIG. 4 is a side elevational view thereof; and

FIG. 5 is a rear elevational view thereof.

I claim:

The ornamental design for a lavatory fitting, as shown.
